DOMESTIC APPLIANCE

John B. Dyer, Dayton, Ohio, assignor to General
Motors Corporation, Dayton, Ohio, a corpora-
tion of Delaware

Application November 30, 1940, Serial No. 368,025

5 Claims. (Cl. 38—61)

This invention relates to domestic appliances and more particularly to ironing machines.

An object of this invention is to provide an ironing machine of the type having a rotatable ironing member and a relatively stationary ironing member with a unitary manipulator or pedal control which causes the rotatable ironing member to stop with said ironing members spaced apart in the first or "off" position of said manipulator, causes said ironing members to be brought together and said rotatable ironing member to be rotated at a first speed in the second position of the manipulator or foot pedal, and causes the rotatable member to be rotated at a second speed, while maintaining said ironing members together in the third position of said manipulator or foot pedal.

Further objects and advantages of the present invention will be apparent from the following description, reference being had to the accompanying drawing, wherein a preferred form of the present invention is clearly shown.

In the drawing:

Fig. 1 is an elevation somewhat diagrammatic, of an ironing machine embodying my invention;

Fig. 2 is a vertical cross-section, somewhat diagrammatic, of a portion of Fig. 1, taken transversely thereto; and

Fig. 3 is a control diagram.

An ironing machine embodying features of my invention may include a rotatable ironing member 10, a relatively stationary ironing member 11, a motor 12, and a transmission 13, all suitably mounted on a table or pedestal 14. The foregoing instrumentalities are of the usual type, in which the member 10 may be a padded roller, and the member 11 may be a shoe rockably mounted about the fulcrum 15. The transmission 13 is of the character which rotates the roller 10 and brings the shoe 11 in contact with the roller 10 upon the movement of a control lever or transmission controller 16. A transmission of the character disclosed in the patent to Foley No. 1,970,511, patented August 14, 1934, may be used, such transmission being slightly modified, if necessary, and within the skill of those familiar with this art. The controller 16 corresponds to member 113 of the Foley patent. A unitary manipulator or pedal 17 is provided, and may be swingingly supported on the bar 18 with a spring or weight, not shown, normally tending to maintain the pedal 17 in an upper, or "off" position. The pedal 17 is connected by the rod 19, lever 20 and lost motion rods 21 and 22 with the transmission controller 16 and with a switch 23 which controls the operation of the motor 12. The rod 21 is slidably mounted on the rod 22 with an interposed spring 24, the construction being such that upon the first movement of the rod 21 upward, the rod 22 also is moved up-

ward to move the controller 16 in its operative position. Thereafter, upon further movement upward of the rod 21, the spring 24 allows the lost motion to become effective and thus permits upward movement of the rod 21 without a corresponding upward movement of the rod 22.

The rod 21 is connected to the lever 25 of the switch 23 in such a manner that the lever 25 moves the switch 23 to the "off" position, first motor speed, and second motor speed respectively when the lever 17 is in its first or "off," second and third positions respectively.

The motor 12 is provided with first and second speed windings, such as to cause its drive shaft to rotate at first and second speed respectively when the corresponding windings are energized. These windings are controlled by the switch 23 in the second and third positions of the switch. The transmission 13 may include a speed reduction train and a station clutch corresponding to members 42, 50, 54, 66 etc. of Foley.

The shoe member 11 is provided with the usual heating resistance 30 under the control of a conventional "on" and "off" hand switch 31, see Fig. 3, to connect it to the source of power L—L₁. Switch 31 may be concealed within the housing which encloses the transmission 13 and it may have its operating lever or button extending outwardly of this housing at any desired location.

In the operation of the ironer, the switch 31 is first closed to heat the shoe heating element 30, and the shoe 11 is allowed to be heated to proper temperature. Thereafter articles to be ironed are placed on the roller 10, and the pedal 17 is depressed to the second position 17a. This causes the controller 16 to be moved to the dotted line position, and the switch 23 to be moved to position 23a. This energizes the first speed winding 32 of the motor 12 and causes the roller 10 to be rotated at the first speed and the shoe 11 to be moved against the roller 10 through the medium of a suitable or conventional station clutch transmission associated with the transmission 13. If the speed at which the roller 10 rotates is not the desired speed, the pedal 17 may be depressed to its third position 17b, which moves the switch 23 to the position 23b and this energizes the second speed winding 33 of the motor 12. This causes the roller 10 to be rotated at a second speed, while the shoe 11 is maintained against the roller 10. If desired, a fourth position of pedal 17 may be provided below 17b, which moves the switch 23 to the open position 23c below 23b (in Fig. 3). In this position the shoe 30 remains in contact with roller 10; but the motor 12 and roller 10 stop rotating. This is a "press" position.

I prefer to cause roller 10 to rotate at relatively low speed when the pedal is on position 17a, and

60 to rotate at a high speed when the pedal is on

position 11b, although this may be changed if desired to cause the roller 10 to operate at high and low speeds when the pedal is in positions 11a and 11b respectively.

While the form of embodiment of the invention as herein disclosed, constitutes a preferred form it is to be understood that other forms might be adopted, all coming within the scope of the claims which follow.

What is claimed is as follows:

1. An ironing machine comprising a rotatable ironing member, a relatively stationary ironing member, a motor, transmission mechanism between said motor and ironing members for rotating said rotatable member and for bringing said ironing members together, a pedal, said pedal controlling the said ironing members, transmission and motor to stop said rotatable member with said stationary member spaced from said rotatable member when said pedal is in an "off" position, to bring together said ironing members and to rotate said rotatable member at a first speed when said pedal is in a second position, and to rotate said rotatable member at a second speed, while maintaining said ironing members together when said pedal is at a third position, first and second speed windings for said motor, a switch connecting said windings selectively to a source of power, a transmission controller for causing said transmission to bring said ironing members together, said pedal having connections with said switch and transmission controller such that in the first position of said pedal, said switch is open and said ironing members are separated, in the second position of said pedal said transmission controller is actuated to bring said ironing members together and said switch connects said first speed winding to said source of power, and in the third position of said pedal said switch connects the said second speed winding to said source of power, and said pedal maintains said transmission controller to maintain said ironing members together.

2. An ironing machine comprising, a rotatable ironing member, another ironing member with relative movement towards and away from said rotatable ironing member, a motor, transmission means to cause said motor to rotate said rotatable member and to bring said ironing members together, said motor having a plurality of running windings adapted to be selectively connected with a source of power, a movable manipulator having a connection with said transmission means for rendering the same effective to rotate said rotatable member and to bring said ironing members together, and means operable upon initial movement of said manipulator for connecting one of said motor windings with said source of power to rotate said rotatable member at one speed and for connecting another of said motor windings with said source of power upon further movement of said manipulator to rotate said rotatable member at another speed while said connection with said transmission means causes said motor to rotate said rotatable member and to bring said ironing members together.

3. An ironing machine comprising, a rotatable ironing member, another ironing member with relative movement towards and away from said rotatable ironing member, a motor, transmission means to cause said motor to rotate said rotatable member and to bring said ironing members

together, said motor having a low speed and a higher speed running windings adapted to be selectively connected with a source of power, a movable manipulator having a connection with said transmission means for rendering the same effective to rotate said rotatable member and to bring said ironing members together, and means associated with said connection and operable thereby upon initial movement of said manipulator for connecting said low speed motor winding with said source of power to rotate said rotatable member at a slow speed and for connecting said higher speed motor winding with said source of power upon further movement of said manipulator to rotate said rotatable member at a faster speed while said connection with said transmission means causes said motor to rotate said rotatable member and to bring said ironing members together.

4. An ironing machine comprising, a rotatable ironing member, another ironing member with relative movement towards and away from said rotatable ironing member, a motor, transmission means to cause said motor to rotate said rotatable member and to bring said ironing members together, a pedal, said motor including first and second speed windings, a switch for connecting said windings selectively to a source of power, said pedal having connections with said switch and said transmission means such that in the normal position of said pedal said switch is open and said ironing members are separated, in the first position of movement of said pedal said connections are actuated so that said transmission means causes said motor to rotate said rotatable member and to bring said ironing members together and said switch is moved to connect said first speed motor winding to said source of power for rotating said motor at one speed, and in the second position of movement of said pedal said connections are actuated to move said switch to connect said second speed motor winding to said source of power for rotating said motor at another speed.

5. An ironing machine comprising, a rotatable ironing member, another ironing member with relative movement towards and away from said rotatable ironing member, a motor, transmission means to cause said motor to rotate said rotatable member and to bring said ironing members together, said motor having a plurality of running windings adapted to be selectively connected with a source of power, a movable manipulator having a connection with said transmission means for rendering the same effective to rotate said rotatable member and to bring said ironing members together, and means operable upon initial movement of said manipulator for connecting one of said motor windings with said source of power to rotate said rotatable member at one speed and for connecting another of said motor windings with said source of power upon further movement of said manipulator to rotate said rotatable member at another speed while said connection with said transmission means causes said motor to rotate said rotatable member and to bring said ironing members together, and on further movement of said manipulator to stop rotation of said rotatable member while said connection with said transmission means maintains said ironing members together.

JOHN B. DYER.
